(57) **CLAIM**

The ornamental design for a case for a portable handheld electronic device, as shown and described.

DESCRIPTION

FIG. 1 is a front perspective view of a case for a portable handheld electronic device;

FIG. 2 is a back perspective view of the case for a portable handheld electronic device of FIG. 1;

FIG. 3 is a front view of the case for a portable handheld electronic device of FIG. 1;

FIG. 4 is a back view of the case for a portable handheld electronic device of FIG. 1;

FIG. 5 is a left side view of the case for a portable handheld electronic device of FIG. 1;

FIG. 6 is a right side view of the case for a portable handheld electronic device of FIG. 1;

FIG. 7 is a top view of the case for a portable handheld electronic device of FIG. 1; and,

FIG. 8 is a bottom view of the case for a portable handheld electronic device of FIG. 1.

The broken lines in FIGS. 1 and 3 depict environmental subject matter that forms no part of the claimed design.

1 Claim, 6 Drawing Sheets
